ATTYS.

UNITED STATES PATENT OFFICE.

CHARLES C. KELLER, OF CLEVELAND, OHIO.

LAVATORY.

1,213,207.

Specification of Letters Patent. Patented Jan. 23, 1917.

Application filed February 28, 1914, Serial No. 821,633. Renewed November 27, 1916. Serial No. 133,810.

To all whom it may concern:

Be it known that I, CHARLES C. KELLER, a citizen of the United States, residing at Cleveland, in the county of Cuyahoga and State of Ohio, have invented a certain new and useful Improvement in Lavatories, of which the following is a full, clear, and exact description, reference being had to the accompanying drawings.

10 This invention relates to lavatory basins and has for its objects the provision of a device of this character which shall be very inexpensive to manufacture and install, attractive in appearance, simple and reliable in construction, highly sanitary, and containing in itself all of the essentials of a complete lavatory outfit. The mode in which these objects are attained, together with other objects and advantages will be made 15 clear in the following description.

In the installation of plumbing fittings at the present time it is customary, prior to the lathing of a house, to place in position the main supply vent and waste pipes, complete with necessary elbows, ventilating fittings, and the like, then cap or close these outlets, test the whole under pressure to ascertain as to the tightness of the joints, then leave everything until after the completion 25 of the lathing and plastering after which the lavatories, etc., are attached in place, the pipe stoppers removed and the various supply and waste connections utilized in their intended manner.

30 My invention contemplates a construction of the various parts, fittings, etc., such as will permit a greater proportion of the work to be done during the roughing in process, when the work is cheaper, and to facilitate 35 the final installation when the workmanship is more expensive.

Other aspects of my invention relate to features of construction as will be obvious.

In the drawings accompanying and forming 40 a part of this application I have illustrated one embodiment of my invention, although it will be obvious that the same is only one of many constructions by means of which the objects in view can be attained.

45 In these drawings Figure 1 is a vertical, cross-sectional view through the center of a lavatory of my preferred construction, illustrating the same in place upon a wall or partition; Fig. 2 is a front elevational view of 50 the same, a portion of the wall plaster being broken away to show the wall plate; Fig. 3

is a perspective view of the preferred form of wall plate.

Describing the parts by reference character, 1 represents the wall plate by means of which the lavatory basin is secured in place. This member is preferably made of the general shape of the letter I as shown in full and dotted lines in Fig. 2, and comprises a central body portion 2 having at each end a 55 pair of laterally extending arms, those at the upper end being illustrated at 3^a—3^a and those at the lower end at 3^b—3^b. All of these arms are of sufficient length to be secured to the studding 4, as shown in Fig. 2 so as to 60 support the portion 2 in upright position between adjacent studs. The rearward sides of the arms 3^a—3^a are preferably formed with horizontal ribs 5 running from side to side thereof which impart added stiffness to 75 the wall plate and also serve to space the forward face of the same away from the studs so as to come substantially flush with the surface of the plaster.

The forward faces of the arms 3^b—3^b are 80 preferably formed with ribs 6—6 adapted to receive the plaster, the body portion of the wall plate being formed at this point with a raised ledge 7 having a flat smooth face located in the same plane as the forward faces 85 of the arms 3^a—3^a. When the plate is secured in place and the wall has received its first coat of plaster the arms 3^b—3^b are concealed from view and only a T shaped portion is left in sight. This may or may not 90 be covered by the second coat of plaster, but is scraped clean in any case before attaching the basin.

Formed integrally with the body portion 2 of the wall plate at the rearward side 95 thereof is a hollow boss 8 having at its lower portion an opening 9 which opens through the forward face of the wall plate, and having its upper end merging with a pipe connection 10. This pipe connection may be 100 formed to receive waste and ventilation pipes in any desired direction, but is preferably formed with a downwardly opening socket 11 adapted for the reception of a waste pipe 12 leading vertically downward 105 within the partition, and with a second socket 13 axially above the socket 11 and adapted for the reception of a vent pipe 14 leading upwardly within the partition. The intermediate portion of the boss 8 forms a 110 hollow chamber 15 communicating at its lower end with the opening 9 and at its up-

per end with both the pipes 12 and 14 for a purpose to be hereafter described.

The later applied portion of the lavatory is preferably made of a single casting and comprises a basin portion 20 with ledge 21, skirt 22, back 23 and shelf 24. The back 23 is preferably substantially vertical and extends from one side of the lavatory to the other at a little distance from the rearward edge as shown, being formed at the end with returns adapted to fit against the surface of the plaster or the face of the wall plate. At the middle of this wall there is formed a vertical niche 26, preferably of generally semi-cylindrical shape having an arched top 27 as shown in Figs. 1 and 2. The rear wall of this niche is substantially flush with the rear edges of the returns and of the skirt 22 and shelf 24 so as to rest snugly against the face of the wall plate when the lavatory is installed, and also is extended downwardly so as to form the rearward wall of the basin proper as illustrated in Fig. 1.

Depending from the bottom of the basin portion 20 is a vertical leg 27 having a flat rearward face adapted to engage the forward face of the ledge 7, and also preferably formed with an integral cylindrical nipple 28 adapted to project into the aperture 9. This leg and nipple are hollow as at 29 to form a discharge passageway, and may be formed with a cleanout at 30 if desired.

The inlet and outlet valves are preferably located behind the wall 23, one at each side of the niche 26, and communicate with this niche by means of discharge spouts 39-39 and mouths 40-40. The valve handles are shown at 55-55, and any suitable type of valve mechanism may be employed. Preferably these valves perform their part in securing the upper part of the lavatory in place, the lower portion of the lavatory being attached by means of a screw 60 or other appropriate fastening member. Leakage between the two portions of the waste connection is prevented by means of a gasket 61 or other appropriate device.

When the basin is secured in place as shown in Fig. 1 the passageway 29 and chamber 15 operate in conjunction to form a trap, one part of same being formed with the wall plate and the other with the basin.

The chamber 15 is preferably larger at the top than at the bottom so as to inhibit siphonage, while the fewness of parts minimizes leakage. The aperture 9 is preferably formed with internal threads so as to permit the application of a stopper for testing purposes during the roughing-in operation, or so as permanently to close the opening if no basin should be required. In the case of office buildings, apartments, etc., where many tenants must be accommodated

and different layouts anticipated, it is frequently desirable to have a larger number of basin stations than of actual basins so as to permit shifting in accordance with varying needs or preferences. The present invention serves this requirement particularly well, especially if the second plaster coat be drawn over the face of the ledge 7, since the contour of the wall is scarcely broken and a basin can be installed at any time with great ease. Also the various pipes are held in position more solidly than is usually the case, since they are secured rigidly to a metal member carried by the partition studs.

For regulating the outflow from the bowl 20 I prefer the arrangement shown in Fig. 1, comprising a hollow tube 65 secured in upright position within the niche 26 and having at its lower end an enlarged portion 66 adapted to seat in the upper end of the discharge passageway. The upper end of the tube is shown as passing through the substantially cylindrical aperture of a ring 67, the latter being pivoted upon a horizontal axis to a suitable bracket affixed to the rear wall of the niche. The upper end of the tube may be provided with a bail by which it can be grasped, and the ring 67 with a projection 71 by which it may be lifted. When the tube is in elevated position, the clamping effect of the ring will prevent its falling to its seat. When it is desired to close the outlet it is sufficient merely to raise the projection 71 whereupon the tube will be released and close the opening.

Having thus described my invention, what I claim is:

1. In a lavatory, a cast metal member adapted to be secured to a wall between adjacent studs, pipe connections rigid with said member, upon the rearward side thereof, there being a chamber in said member adapted to form part of a trap, a basin adapted to contact with and be secured to the face of said member, and having a hollow portion adapted to form another part of a trap and means for securing said basin to said member, so as to support the same and complete said trap.

2. In a lavatory, a rigid member adapted to be secured to a wall and having a chambered portion, said chambered portion having an inlet on the forward side of said member and an outlet at the rearward side of said member, said inlet being at a lower level than said outlet, a basin member having a rearward face adapted to be secured to the forward face of said first member, said basin member having a chambered portion provided with inlet and outlet, the outlet of the basin chamber being at a lower level than its inlet and arranged to register with the inlet of said first chamber when said basin mem-

ber is secured to said wall member, and means for securing said basin member to said wall member.

3. In a lavatory, a member adapted to be secured to a wall with its front face near the surface of said wall, pipe connections rigid with said member and located rearwardly from its face, a basin member having a face complementary to that of said wall member and adapted to be secured thereto, said wall member and basin member being formed with trapped discharge passageways, one half of such trap being formed in each of said members, and means for securing said basin member to said wall member.

4. In a lavatory, a cast member adapted to be secured to a wall and having a substantially flat forward face adapted to lie substantially at the plane of the wall, said member being formed with a hollow chamber communicating at its lower portion with an aperture in said forward face and also having a discharge opening at its upper portion, a basin member having a rearward face complementary to the face of said wall member and adapted to be secured thereto, the basin having a downwardly extending discharge passageway which opens through the face of the basin member and is arranged to register with the first mentioned aperture of said chamber, means for securing said basin member to said wall member, and means for maintaining a tight joint between the walls of said openings.

5. In a wall lavatory a cast metal plate having a substantially flat elongated body portion and laterally extending arms at each end and parallel to the plane thereof, the arms at one end having ribs upon their rearward sides, and the arms at the other end having ribs upon their forward sides,

said last named ribs terminating to the rear of the plane which defines the forward face of said body portion.

6. In a wall lavatory a cast metal wall plate having a substantially flat elongated body portion and laterally extending arms at each end and parallel to the plane thereof, said arms being perforated for the reception of securing members whereby they may be attached to wall studs, the arms at one end of said plate having ribs at their rearward sides arranged to engage the forward faces of the studs and the combined thickness of arms and studs being substantially equal to the thickness of the lath and plaster, the arms at the other end of said plate having their rearward faces substantially in the same plane with the rearward edges of said first ribs and also having other ribs upon their forward faces which terminate at the rear of the plane which defines the forward face of said body portion, said body portion being arranged for the reception of pipe members and a basin member.

7. In a wall lavatory, a wall plate having a body portion arranged to be secured to a wall between adjacent studs and having arms adapted to be secured to the faces of those studs, certain of said arms being formed with ribs upon their outer faces for the reception of plaster, and said body portion being of a thickness to project beyond said plaster and being formed for the reception of pipe members and of a basin member.

In testimony whereof, I hereunto affix my signature in the presence of two witnesses.

CHARLES C. KELLER.
